UNITED STATES PATENT OFFICE.

RALPH L. CHESTER AND HARVEY Y. LAKE, OF OCEAN CITY, NEW JERSEY.

DESIGN FOR A BADGE.

51,717.

Specification for Design.

Patented Feb. 5, 1918.

Application filed November 27, 1917. Serial No. 204,294. Term of patent 7 years.

To all whom it may concern:

Be it known that we, RALPH L. CHESTER and HARVEY Y. LAKE, citizens of the United States, residing at Ocean City, in the county of Cape May and State of New Jersey, have invented a new, original, and ornamental Design for a Badge, of which the following is a specification, reference being had to the accompanying drawing, forming a part thereof.

Fig. 2 is an elevation of the opposite face of the badge illustrating our new design.

We claim:

The ornamental design for a badge, as shown.

RALPH L. CHESTER.
HARVEY Y. LAKE.

Witnesses:

CHAS. E. POTTS,
MARY A. INGLAR.
